UNITED STATES PATENT OFFICE

WILLIAM DEMUTH, OF NEW YORK, N. Y.

DESIGN FOR SMOKING-PIPES.

Specification forming part of Design No. 11,277, dated July 1, 1879; application filed May 21, 1879.
[Term of patent 7 years.]

To all whom it may concern:

Be it known that I, WILLIAM DEMUTH, of the city, county, and State of New York, have originated and designed a new Pattern for Smoking-Pipes, of which the following is a full, clear, and exact description, reference being had to the accompanying drawing, making part of this specification.

The drawing represents a side view.

This design relates to a bowl, which resembles in appearance a tomahawk, being provided with a projection on one side, which appears to be the prolongation of the stem, while the bottom part of the bowl is ornamented by a hemispherical cap or helmet with a sharp-pointed apex.

In the drawing, the letter A designates the bowl of my pipe, the body of which has flaring sides *a a* and a curved edge, *b*, which, at its junction with the sides *a a*, appears to form sharpened corners *c c*, so that a side elevation of said bowl has the resemblance of a tomahawk. From one side of this bowl extends the

stem B, and from its opposite side extends a projection, C, which appears to form the prolongation of the stem. The bottom of the bowl A is ornamented by a semicircular groove, *d*, a hemispherical cap or helmet, *e*, and a spur or apex, *f*.

What I claim as new, and desire to secure by Letters Patent, is—

The design for a tobacco-pipe, consisting of a bowl, A, having curved edge *b*, flaring sides *a a*, and terminating at its bottom in a hemispherical cap or helmet, *e*, provided with a spur, *f*, and the stem B, projecting from near the lower end of one of the flaring sides, and the projection C, extending from the opposite side in line with the stem, all as shown and herein described.

In testimony that I claim the foregoing I have hereunto set my hand and seal.

WM. DEMUTH. [L. S.]

Witnesses:

CHAS. T. LUNT,
E. F. KASTENHUBER.
